DESIGN FOR A TIE RACK

William Grant Williams, Anaheim, Calif.

Application September 4, 1944, Serial No. 115,190

Term of patent 7 years

(Cl. D33—8)

To all whom it may concern:

Be it known that I, William Grant Williams, a citizen of the United States, residing at Anaheim, in the county of Orange and State of California, have invented a new, original, and ornamental Design for Tie Rack, of which the following is a specification, reference being had to the accompanying drawing forming part thereof.

Figure 1 is a top plan view of a tie rack embodying my new design; and Fig. 2 is a view in side elevation of the same.

I claim:

The ornamental design for a tie rack, as shown.
WILLIAM GRANT WILLIAMS.
